CHANNEL SELECTOR CONTROL UNIT

Murray A. Grabin and Alfred C. Oechsle, Los Angeles, Calif., assignors, by mesne assignments, to Alliance Manufacturing Company, Division of Consolidated Electronics Industries Corporation, Alliance, Ohio, a corporation of Delaware

Application March 19, 1956, Serial No. 40,651

Term of patent 14 years

(Cl. D26—14)

Fig. 1.

Fig. 2.

Fig. 3.

Fig. 4.

Fig. 1 is a front elevational view of a channel selector control unit, showing our new design.

Fig. 2 is a side elevational view thereof.

Fig. 3 is an end view as seen from the bottom of Fig. 1.

Fig. 4 is an enlarged fragmentary sectional view, as taken on line 4—4 of Fig. 1.

The top and back of the unit are substantially plain and unornamented.

We claim:

The ornamental design for a channel selector control unit, substantially as shown and described.
